INVENTOR

UNITED STATES PATENT OFFICE

96,576

DESIGN FOR A TEXTILE FABRIC

William R. Haywood, New York, N. Y.

Application April 20, 1935, Serial No. 56,474

Term of patent 3½ years

To all whom it may concern:

Be it known that I, William R. Haywood, a citizen of the United States of America, residing in Manhattan, county of New York, and State of New York, have invented a new, original, and ornamental Design for a Textile Fabric, of which the following is a specification, reference being had to the accompanying drawing, forming part thereof, wherein,

Figure 1 is a plan view of a piece of textile fabric, showing my new design.

Figure 2 is a sectional view of the textile fabric shown in Figure 1, taken along the line 2—2.

The elements in the design consist of a series of vertical bars emerging into circular areas, the bars and outlines of the circles being raised above the surface of the fabric.

I claim:

The ornamental design for a textile fabric, substantially as shown and described.

WILLIAM R. HAYWOOD.
